UNITED STATES PATENT OFFICE.

MARVIN F. GIFFORD, OF NEWAYGO, MICHIGAN.

LOCK FOR IGNITION CIRCUITS.

1,424,298.

Specification of Letters Patent. Patented Aug. 1, 1922.

Application filed August 12, 1920. Serial No. 403,034.

To all whom it may concern:

Be it known that I, MARVIN F. GIFFORD, a citizen of the United States, and a resident of the city of Newaygo, in the county of Newaygo and State of Michigan, have invented a new and useful Improvement in Locks for Ignition Circuits, of which the following is a full, clear, and exact description.

My invention relates to improvements in locks for ignition circuits, and it consists in the combinations, constructions and arrangements herein described and claimed.

An object of my invention is to provide a locking device for ignition or like circuits provided with means for breaking the circuit at the will of the operator and with means for preventing the reestablishment of the circuit thus broken until the last named means are operated in the manner known only to the operator.

A further object of my invention is to provide a device of the type described that is designed primarily for use in an automobile or other automotive vehicle wherein the device may be operated in the manner set forth above, thereby reducing the possibility of theft of the car since the same cannot be driven under its own power by any one not possessing the requisite knowledge as to the steps to be taken in operating the device.

A further object of my invention is to provide a device of the type described that is relatively simple in construction and operation, not likely to get out of order easily, and thoroughly practical commercially.

A further object of my invention is to provide a device of the type described that can be applied to an automobile or the like without the necessity of making any extensive changes, if any, in construction of the latter.

Other objects and advantages will appear in the following specification, and the novel features of the invention will be particularly pointed out in the appended claims.

My invention is illustrated in the accompanying drawings, forming part of this application, in which

Figure 1 is a plan view of the device with the cover therefor removed,

Figure 2 is a longitudinal section through the device,

Figure 3 is a reduced plan view of the device showing the cover in place.

In carrying out my invention, I provide a casing 1 formed with a marginal outwardly

extending flange 2 around its upper edge adapted to support the cover 3 which may be secured thereto in any suitable manner as by means of bolts 4. A handle 5 is provided with a spindle portion 7 projecting through the cover and mounted therein for free rotatable movement. A dial 6 is rigidly secured to the handle 5, being carried thereby exterior the cover 3. Disks 8 and 9 are loosely mounted upon the spindle 7, the disk 8 being spaced from the inside wall of the cover 3 by a spacing member 10 while the disk 9 is spaced from the disk 8 by a spacing member 11. A third disk 12 is keyed to the spindle 7 near its end and is held on the spindle by a nut 13. A spring 14 mounted upon the spindle 7 is interposed between the disks 12 and 9 to maintain the same in spaced relation.

The disks 8, 9 and 12 are each formed with a plurality of spaced apart openings 15, 15^a, 15^b and 15^c, respectively around their outer edges. These openings coincide with graduation 19 of a scale that is delineated upon the dial 6. A pin 16 is inserted through any one of the openings 15 in the disk 8. A pin 17 is projected through one of the openings 15^a in the disk 9. A pin 18 is placed in one of the openings 15^b in the disk 12. Operation of the handle 5 in accordance with the combination decided upon will cause the disks 8, 9 and 12 to be rotated until notches 20, 20^a and 20^b, respectively in edges of the three disks are in registration. This will be accomplished since the pin 17 will contact with the pin 16 when the disk 9 is rotated while the position of both disks 9 and 8 will be determined by operation of the disk 12 since the pin 18 will contact with the pin 17.

When the notches 20, 20^a and 20^b in the edges of the three disks are in registration the upright portion 21 of the detent 22 is received therein. The detent 22 extends through the guide way 24 and connects with or may be formed integrally with a slideable carrying plate 23. Shoulders 26 being formed at juncture of the detent 22 and the carrying plate 23 to limit the movement of the latter toward the disks. The guide way 24 is secured to the bottom of the casing 1 in suitable manner as by means of screws or rivets 25.

The carrying plate 23 is formed with opposite laterally extending arms 27-27 which are curved at their ends toward the disks and formed with upright end portions 28-28 to 110

which is secured a non-conducting bar 29. The bar 29 may be secured to the upright end portions in any suitable manner as by means of rivets 30. It will be observed that 5 the ends of the bar 29 project laterally beyond the arms 27-27. Secured to the bar 29 at 31-31 is a conducting connector bar 32.

When the detent 22 is received within the 10 registering notches in the disks as pictured in Figure 1 of the drawings, the contact bar 32 is in contact with conducting contact bolts 33-33 that are projected through openings in the upright end members 35-35 15 of supporting plates 34-34 and are maintained in position relative to the connector bar 32 by springs 36-36 interposed between studs 37-37 and the rearward end members 35-35. Collars or washers 38-38 20 that are formed of a resilient material are secured on the conducting bolts 33 and form bumpers to limit the movement of the bolts against the impact of the contact bar 32.

Secured to one of the conducting contact 25 bolts 33 is an insulated electrical conducting wire 39 that is passed around the interior walls of the casing 1 and is secured at its other end to a binding post 42 that projects through the wall of the casing 1. This connection may be established in any suitable manner as by means of a nut 44 screwing on the end of the binding post 42. An insulating washer 43 is interposed between the end 30 of the conducting wire and the wall of the casing 2. A similar insulated conducting wire 40 is connected with the other one of the conducting contact bolts 33 and is extended around the inside wall of the casing 2. The other end of the conducting wire 40 35 is secured to a binding post 41 that projects through the wall of the casing 1. An insulating washer 43 is placed upon the binding post to insulate the wall of the casing 1 from the conducting wire 40 which is 40 maintained on the binding post by means of a nut 44.

Exterior of the casing 1, the binding posts 41 and 42 are connected with adjacent ends 45 of a conducting wires 45 that forms a part 50 of the conducting means provided in an ignition or like circuit in which the device is placed, insulating washers 46 are placed on the binding posts to insulate the conducting wires 45 from the wall of the casing 1. The 55 conducting wires 45 may be connected with the binding posts in any suitable manner as by being maintained thereon by means of nuts 47.

The carrying plate 23 is extended through 60 the guideway 48 that is secured to the bottom wall of the casing 1 by screws or rivets 49 and is further guided in its movement by an upright pin or stud 50 that projects from the floor of the casing 1 and is received in a guide slot 51 provided in the

carrying plate 23. The carrying plate 23 has an upwardly bent end portion 53. A tension spring 52 is secured at one end to the pin 50 and at its other end to a hook 54 carried by the upright end portion 53 70 tends to hold the carrying plate 23 in the position shown by full lines in Figure 1; that is, with the detent 22 disposed within the registering notches in the disks.

A handle 55 positioned exterior the cover 75 3 has a shank or stem 56 extending through the cover with its extreme end received within a slot 57 that is provided in the carrying plate 23. A disk 58 that is eccentrically mounted on the stem 56 and therefore serves 80 as a cam member, may be operated by turning the handle 55 a half revolution to move the carrying plate 23 into the position shown by the dotted lines in Figure 1, thereby moving the connector plate 32 out of contact with the conducting contact bolts 33 and breaking the ignition circuit of which the wires 39 and 40 constitute a part. When the carrying plate 23 occupies the position shown by the dotted lines in Figure 1, the 85 detent 22 has been withdrawn from the registering notches in the disks. The handle 5 may then be turned to rotate the disks 8, 9 and 12, thereby moving the notches in the disks out of registration. Consequently 90 the handle 5 must be again moved in accordance with the combination decided upon to cause the registration of the notches, 20, 20^a, and 20^b before the circuit can be closed since the detent 22 must enter the registering 100 notches 20 before the connector plate 32 can contact with the ends of the conducting contact bolts 33.

The cam member 58 is enlarged at 59, the enlarged portion thereof being formed 105 with a recess 60. When the cam member 58 has been moved into the position indicated by the dotted lines in Figure 1 it may be locked in this position. To accomplish this object, I provide a lock 62 that 110 is of the cabinet lock type and may be of any suitable construction. The lock 62 is mounted upon a block 63 secured to the bottom of the casing 1 and has a cylinder 64 thereof projecting through an opening 115 in the cover 3. A key (not shown) may be inserted in the cylinder 64 to operate the lock bolt 65, thereby causing the projection of the latter through an opening 61 in the end portion 53 of the carrying plate 23 into the recess 60 in cam member 58. Consequently, the circuit cannot be closed until the cam member 58 has been released by operation of the lock 62 and the handle 5 has then been operated in accordance with the 120 combination decided upon.

From the foregoing description of the various parts of the device the operation thereof may be readily understood and requires no detailed description. In service 125 130

the device would be suitably positioned in an automobile in such a manner as to permit the wires 39 and 40 being incorporated in the regular ignition circuit. The casing 5 of the lock will be secured to the dash board or other suitable portion of the car where the handles 5 and 55 can be conveniently operated. The casing 1 may be lined with a suitable insulating material (not shown) 10 as an additional safe guard against short circuiting.

I claim:

1. A locking device for an electrical circuit comprising a casing, a pair of conducting contact members disposed therein, a slideable carrying plate disposed in said casing, said carrying plate being formed with a detent at one end thereof, means for guiding said carrying plate in its slideable movement, 20 a conducting connector carried by said carrying plate, a stem mounted in said casing for rotatable movement, a plurality of disks mounted on said stem, each of said disks being provided with a notch in its peripheral 25 edge, tension means for normally holding said connector in contact with said members and said detent in the registering notches in said disk, means for occasioning movement of said carrying plate to move said connector 30 out of contact with said contact members and to withdraw said detent from said registering notches, and means for operating said disks to lock said carrying plate in said last named position, wherefore re-closing of 35 the circuit is prevented.

2. A locking device for an electrical circuit comprising a casing, a pair of conducting contact members disposed therein, a slideable carrying plate disposed in said casing, 40 said carrying plate being formed with a detent at one end thereof, means for guiding said carrying plate in its slideable movement, a conducting connector carried by said carrying plate, a stem mounted in said casing 45 for rotatable movement, a plurality of disks mounted on said stem, each of said disks being provided with a notch in its peripheral edge, tension means for normally holding said connector in contact with said contact 50 members and said detent in the registering notches in said disk, means for occasioning movement of said carrying plate to move said connector out of contact with said contact members and to withdraw said detent 55 from said registering notches, means for operating said disks to lock said carrying plate in said last named position, wherefore re-closing of the circuit is prevented, and an auxiliary locking means for maintaining said 60 carrying plate in its last mentioned position.

3. A device of the character described comprising a casing, two separate substantially stationary contact members disposed within the casing, a slideable carrying plate 65 disposed within the casing and formed in-

termidately with oppositely extending lateral arms, a conducting connector secured to said arms and adapted to engage said contacts when the carrying plate has been moved in one direction into one position and 70 to disengage the contacts when the carrying plate is moved in the opposite direction, a combination locking mechanism partially disposed within the casing and operable exteriorly of the casing to permit or to prevent movement of the carrying plate in the first named direction, and tensional means 75 connected with the carrying plate and arranged to urge the latter in the first named direction.

4. A device of the character described comprising a casing, two separate substantially stationary contact members disposed within the casing, a slideable carrying plate disposed within the casing and formed in 80 intermidately with oppositely extending lateral arms, a conducting connector secured to said arms and adapted to engage said contacts when the carrying plate has been moved in one direction into one position and 85 to disengage the contacts when the carrying plate is moved in the opposite direction, a combination locking mechanism partially disposed within the casing and operable exteriorly of the casing to permit or to prevent movement of the carrying plate in the first named direction, tensional means connected with the carrying plate and arranged 90 to urge the latter in the first named direction, and means operable exteriorly of the 95 casing for moving the carrying plate in the second named direction against the action of the tensional means.

5. A device of the character described comprising a casing, two separate substantially stationary contact members disposed within the casing, a slideable carrying plate disposed within the casing and formed in 100 intermidately with oppositely extending lateral arms, a conducting connector secured to said arms and adapted to engage said contacts when the carrying plate has been moved in one direction into one position and 105 to disengage the contacts when the carrying plate is moved in the opposite direction, a combination locking mechanism partially disposed within the casing and operable exteriorly of the casing to permit or to prevent movement of the carrying plate in the first named direction, tensional means connected with the carrying plate and arranged 110 to urge the latter in the first named direction, means operable exteriorly of the casing for moving the carrying plate in the second named direction against the action of the 115 tensional means, and other means for locking said carrying plate against movement in the first named direction.

6. A device of the character described comprising a casing, two separate contact 120

members, means for yieldingly maintaining said contact members in determined relative positions, a slidable carrying plate disposed within the casing and formed intermediately with oppositely extending lateral arms, a conducting connector secured to said arms and adapted to engage said contacts when

the carrying plate has been moved in one direction into one position and to disengage the contacts when the carrying plate is moved in the opposite direction, and means carried by the casing for controlling the movements of the slidable carrying plate.

MARVIN F. GIFFORD.
